PROJECT-RETRACT MECHANISM FOR A BALL-
POINT WRITING INSTRUMENT

Curtis L. Malm, Norwalk, Calif., assignor to Paper Mate
Manufacturing Company, Santa Monica, Calif., a cor-
poration of Delaware

Filed Jan. 31, 1963, Ser. No. 255,325
5 Claims. (Cl. 120—42,03)

This invention relates to an improved writing instrument and more particularly an improved project-retract mechanism for use in a writing instrument of the ball-point type wherein the ball-point is adjustable into a projected position for use in writing and into a retracted position with the ball-point concealed within the pen housing.

The improved project-retract mechanism of the present invention is adapted for use in a ball-point writing instrument of the type embodied in Patent 2,941,510 issued June 21, 1960, wherein an inclinable latch member is carried within a barrel and cooperates with the barrel to hold the writing unit of the pen in alternative projected writing position and retracted carrying position. It is very important that the step of retraction of the writing unit positively and reliably return the writing tip into the pen housing, to permit the pen to be carried in a shirt or coat pocket with assurance that the writing tip will not soil clothing or otherwise stain the pocket with ink. If the pen is thrown into a handbag the other contents of the handbag may become stained or marked up if the tip is not completely retracted. It has been found that repeated use of a pen causes dust, dirt or foreign matter to accumulate and become imbedded in the retract mechanism of prior pens, causing the writing tip to sometimes stick or jam up on the retract motion. The present invention provides a more positive and dependable retract mechanism eliminating the possibility of having the writing unit stick or jam in an undesired projecting position.

If has also been found that dust and dirt sometimes collects on the latch member after repeated and continued use which causes the latch to slip out of engagement with the cooperatively shaped barrel causing the writing unit to be retracted unintentionally. The present invention provides a more positive and reliable engagement feature that requires a positive operation to actuate the retract mechanism.

Accordingly, it is a general object of the present invention to provide a project-retract mechanism that causes a quick, positive and reliable retraction of the writing tip of the ball-point pen.

Another object of the present invention is the provision of a project-retract mechanism that more positively locks the writing unit in alternate projected and retracted positions.

Other objects and advantages of this invention will be readily apparent from the following description when considered in connection with the appended drawings.

In the drawings:

FIG. 1 is a longitudinal view in section and in elevation showing a writing instrument containing a preferred embodiment of the project-retract mechanism of the present invention with the writing tip in the projected or writing position.

FIG. 2 is an enlarged longitudinal view in section and in elevation showing the upper portion of FIG. 1.

FIG. 3 is an enlarged longitudinal view in section and in elevation taken along plane III—III of FIG. 2.

FIG. 4 is an enlarged longitudinal view in section and in elevation similar to FIG. 2 showing the position of the latch immediately after the plunger has been depressed to retract the writing unit.

FIG. 5 is a transverse section taken along plane V—V of FIG. 2.

2

FIG. 6 is a transverse section taken along plane VI—VI of FIG. 2.

FIG. 7 is a longitudinal section similar to FIG. 2 showing the position of the latch in the retracted position.

FIG. 8 is a longitudinal section similar to FIG. 3 taken along plane VIII—VIII of FIG. 7.

FIG. 9 is a longitudinal section showing the position of the latch the instant it engages the project stop shoulder.

FIG. 10 is a transverse section taken along plane X—X of FIG. 7.

FIG. 11 is a transverse section taken along plane XI—XI of FIG. 9.

Referring now to the drawings, wherein like reference characters designate like or corresponding parts throughout the several views, there is shown in FIG. 1 a writing instrument 20 which incorporates the project-retract mechanism 21 of the present invention. The writing instrument 20 has a lower housing portion 26 which is threadably connected to the upper housing portion 27. The writing unit 28 is axially disposed and axially movable within the lower housing portion 26 and extends into the upper housing portion 27. The writing unit 28 has a writing tip 29 at its lower end, a latch seat 30 at its upper end and an intermediate enlarged ink reservoir 31. The writing unit 28 is normally biased toward a retracted position by a spring 34 which may bear on shoulders 32 within the housing at one end and an enlarged section 33 of the writing unit 28 at the other end. Rearward of the writing unit 28 and entirely within the upper housing portion 27 is the project-retract mechanism 21 of the present invention. The project-retract mechanism 21 functions to hold the writing unit 28 in alternate projected or writing position and retracted position.

As best seen in FIGS. 2, 3, 4, 7, 8 and 9 the project-

35 retract mechanism 21 has a barrel 41 which is positioned axially within the upper housing portion 27 and has an axial latch receiving aperture 42. The latch receiving aperture 42 has an upper polygonal portion 43 and a lower portion 44 which may either be cylindrical or polygonal.

40 The lower portion 44 is cooperatively shaped with the latch 51 to prevent the latch from rotating during operation but which does permit the latch to be inclined laterally within the aperture 42. One method of cooperatively shaping the lower portion of the barrel 41 and the latch 51 may

45 be to provide longitudinal grooves 45 in the walls of the aperture 44 parallel to the axis of the aperture 42 adapted to slidably receive outwardly extending guides 53 on the latch 51. Latch 51 is urged upwardly by writing unit 28 and spring 34.

50 The upper polygonal portion 43 of the latch receiving aperture 42 has a pair of opposing, laterally spaced side walls 46a and 46b. The side walls 46a and 46b are provided with a pair of downwardly facing, longitudinally displaced and oppositely inclined project and retract stop

55 shoulders 47 and 48 respectively. The stop shoulders 47 and 48 are adapted to engage and retain latch 51 in alternate projected and retracted positions. As best seen in

FIG. 3 the project stop shoulder 47 is inclined and may

make an acute angle of between 60° and 70° with the axis of the aperture 42. An angle of 64° with the axis

60 of the aperture 42 is preferred. As best seen in FIG. 2 project stop shoulder 47 is also inclined with respect to the side wall 46a. Because of this inclination, project stop shoulder 47 and side wall 46a form an acute dihedral angle. This acute dihedral angle is normally 80°, but may be any acute angle as will become more apparent as this description progresses. This second inclination or undercut provides a more positive engagement or lock

65 on the latch 51 when in its projected position. By under-

70 cutting the project stop shoulder 47 the writing unit 28 cannot easily be retracted by simply dropping the pen or

bumping it. A positive action is needed to retract the writing unit 28.

As best seen in FIG. 8 retract stop shoulder 48 has a lower guide face portion 48a and an upper guide face portion 48b terminating in the retract stop shoulder. The lower guide face portion 48a is inclined to form an acute angle with respect to the axis of the aperture 42. The acute angle formed by the lower guide face 48a and the axis of the aperture 42 may be between 5° and 27°, preferably being 22°. This guide face portion 48a is provided to urge the latch laterally as well as permit it to move longitudinally during the retract motion. By urging the latch laterally back to the retracted position quickly and in this fashion, the possibility that the latch will stick or jam is greatly reduced if not eliminated. The upper guide face portion 48b is inclined opposite to the project stop shoulder 47 and at a similar angle with the axis of the aperture 42. This upper guide face 48b is undercut (similarly to the project stop shoulder) to form an acute dihedral angle with side wall 46b. The undercut upper guide face 48b provides a more positive engagement between the retract stop shoulder 48 and latch 51 when the writing unit 28 is in the retracted position.

Axially positioned within the latch receiving aperture 42 of the barrel 41 is an elongated latch or wobbler 51. The latch or wobbler is inclinably seated on latch seat 30 by means of a cooperatively shaped base 52. The cooperatively shaped base 52 is shaped so that the latch 51 is free to move axially while receiving the upward thrust of the spring biased writing unit 28, and be inclinably laterally within the latch receiving aperture 42. Rotation of the latch about a longitudinal axis is prevented in any suitable manner, as by the guides 53 and grooves 45 (see FIG. 11).

The latch 51 has a pair of opposed upstanding side walls 54a and 54b, a pair of opposed upstanding edge walls 55a and 55b and a top 56. The top 56 of the latch 51 is provided with a pair of laterally spaced and oppositely inclined surfaces 57a and 57b. Each of these inclined surfaces 57a and 57b intersect each of the side walls 54a and 54b to form an upper dihedral angle "a" as best seen in FIG. 3. This dihedral angle "a" is less than 90° and corresponds to the acute angle formed by the project stop shoulder 47 and the upper guide face 48b of the retract stop shoulder 48 with the axis of the aperture 42. This acute angle may normally be within the range of 60° to 70° but preferably is 64° to correspond to the angle of inclination of the stop shoulders 47 and 48b. The inclined surfaces 57a and 57b each intersect one of the edge walls 55a and 55b to form another acute dihedral angle. This second dihedral angle produces an undercut on the inclined surfaces 57a and 57b which corresponds to the undercut on the stop shoulder 47 and upper guide face 48b. This second dihedral angle may normally be within the range of 70°-89° but is preferably 74° to correspond to the dihedral angles formed by the stop shoulder 47 and upper guide face 48b with the side walls 46a and 46b of the barrel 41. The second dihedral angle on the latch 51 is compensated for the inclination of the latch 51 between a retracted position to a projected position. This compensation makes the angle seem different numerically but when the latch is inclined in either the project or retract position the surfaces 57a and 47 or 57b and 48b mate perfectly to form a plane to plane contact between the latch 51 and the barrel 41. This plane to plane undercut engagement produces a reliable and more positive locking between the latch 51 and the barrel 41.

Separating the opposite inclined surfaces 57a and 57b on the top 56 of the latch 51 is an axially projecting central surface 58. This central surface 58 is usually hemispherical in form to produce a positive engagement between the latch 51 and the plunger 61.

Axially positioned within the upper housing portion 27 is a depressible plunger 61. The plunger 61 has an upper knob portion 62 which protrudes beyond the upper hous-

ing portion 27 through an axially aligned plunger receiving aperture 36. Centrally positioned on the plunger 61 is an outwardly flaring flange 63 which is cooperatively shaped with inwardly extending shoulders 35 provided at the upper end of the upper housing portion 27 to retain the plunger 61 within the upper housing portion 27. Opposite the knob portion 62 and slidingly entering the latch receiving aperture upper portion 43 is an elongated lower body portion 64. The lower body portion 64 and the latch receiving aperture upper portion 43 may be cooperatively shaped to prevent rotation of the plunger 61 during successive depressions. At the lower end of the elongated body portion 64 are two laterally spaced oppositely inclined project and retract cams 65a and 65b respectively. These project and retract cams 65a and 65b are inclined laterally, upwardly and outwardly as to continuously urge the hemispherical tip 58 of the latch toward the periphery of the latch receiving aperture 42 when the plunger is depressed into contact with the tip 58. The plunger 61 is biased outwardly toward an undepressed position by a spring 69.

The operation of the project-retract mechanism of the present invention to provide a reliable retraction of the writing unit and to provide a more secure locking of the writing unit in both projected and retracted positions is as follows:

As best seen in FIGS. 1, 2 and 3 with the writing unit 28 in the projected position the latch 51 is inclined in the position where the inclined surface 57a is forced against and mates with the project stop shoulders 47 by receiving the upward thrust of the spring biased writing unit 28. As can best be seen in FIG. 2 the undercutting of the project stop shoulder 47 and the inclined surface 57a on the latch 51 insures a positive locking of the latch 51 in this inclined position thereby assuring the user of the pen that the writing tip 29 will remain in the project or writing position until positive action is taken to retract it. To retract the writing tip 29 plunger 61 is depressed compressing spring 69. The retract cam face 65b of the plunger 61 engages a laterally displaced portion of the hemispherical surface 58 of the latch 51 inclining the latch 51 to the left as seen in FIGS. 2 and 4 while moving the latch 51 axially. The latch 51 is first moved slightly axially until the surfaces 47 and 57a become unmated, then the latch 51 is inclined into the position shown in FIG. 4. The plunger 61 is then released and is forced into the undepressed position by the spring 69. Starting with the latch 51 in the position shown in FIG. 4 the inclined surface 57b of the latch 51 slides quickly along the lower guide face 48a longitudinally and laterally toward the retract position and retract stop shoulder 48. When the inclined surface 57b of the latch 51 reaches the upper guide face 48b it slides the remaining short distance into the retracted position shown in FIG. 8. The undercutting of surface 57b on the latch 51 and upper guide face 48b provides a positive locking of the writing unit 28 in the retracted position. As best seen in FIG. 8 when the latch 51 reaches the upper guide face 48b the spring 34 biasing the writing unit 28 and the latch 51 toward a retract position is just about fully released. If any dirt or dust accumulates on the upper guide face 48b the inclined surface 57b of the latch 51 may stick or jam up so that the retract motion is not completed. Therefore the shorter the distance the inclined surface 57b of the latch 51 has to slide along the upper guide face 48b the more reliable and positive the retract mechanism will be.

To project the writing unit 28 the plunger 61 is depressed compressing spring 69. The project cam face 65a on the plunger 61 engages a laterally displaced portion of the hemispherical end 58 of the latch 51 moving the latch axially as well as inclining the latch 51 toward the right as best seen in FIG. 9. When the latch 51 is moved axially enough to disengage the undercut surface 57b of the latch 51 from the upper guide face 48b the latch 51 is inclined into an opposite direction as best seen in FIG. 9. Edge wall 55b of the latch 51 then slides down side wall 46a of

the barrel 41 until the inclined surface 57a of the latch 51 is below the project stop shoulder 47. The plunger 61 is then released and it is returned to the undepressed position by the spring 69. The inclined surface 57a of the latch 51 and the project stop shoulder 47 are engaged and the inclined surface 57a slides up along the project stop shoulder 47 under the upward biasing force of spring 34 into the writing position as shown in FIGS. 1, 2 and 3. The undercutting of the inclined surface 57a of the latch 51 and the project stop shoulder 47 provides a very positive engagement between the surfaces thereby preventing any accidental actuation of the mechanism 21. A positive action on the plunger is needed to disengage the latch 51 from the project stop shoulder 47.

By providing the dihedrally inclined surfaces and shoulders herein described it has been found that the mechanism is capable of operating positively and dependably for hundreds of thousands of cycles. Dust, debris and normal wear does not deleteriously affect the operation of the mechanism.

Obviously many modifications and variations of the present invention are possible in the light of the above teachings. It is therefore to be understood that within the scope of the appended claims the invention may be practiced otherwise than as specifically described.

I claim:

1. A project-retract mechanism for a writing instrument having a barrel and a writing unit longitudinally movable therein between projected and retracted positions and spring means normally biasing the writing unit toward retracted position, said writing unit having an upper end and a lower writing tip at the other end, comprising:
a hollow barrel having an axially extending latch receiving aperture provided with opposing, laterally spaced side walls,
said side walls having a pair of longitudinally displaced and oppositely inclined project and retract stop shoulders,
the retract stop shoulder presenting a lower guide face portion at a smaller angle to the axis of said aperture and an upper guide face portion at a greater angle to said axis of said aperture, terminating in said retract stop shoulder,
said upper guide face portion and said project stop shoulder having substantially the same acute dihedral angles with said side walls;
an elongated floating latch member contained within said barrel rearwardly of said writing unit,
said latch member being in contact with the upper end of said writing unit, movable with said unit and adapted to receive upward thrust of said spring biased writing unit,
said latch member and said barrel being cooperatively shaped to permit longitudinal sliding and inclination of the latch in opposite lateral directions and to restrain axial rotation of the latch,
said latch having a pair of opposed upstanding edge wall surfaces, a pair of opposed upstanding side wall surfaces and a top including a pair of separate oppositely inclined laterally spaced surfaces separated by a projecting central surface approximating a hemispherical form, said oppositely inclined laterally spaced surfaces adapted to cooperate with said laterally spaced stop shoulders in said barrel to retain said latch in alternately inclined positions of said latch to hold said writing unit in projected and retracted position,
each of said inclined surfaces intersecting said side wall surfaces to form an upper dihedral angle with one of said side wall surfaces of less than 90°, and also intersecting said edge walls to form an upper dihedral angle of less than 90° with one of said edge walls; and
an axially aligned depressible plunger carried by the rear end of said barrel,
said plunger having an upper knob portion, an annular centrally positioned flange adapted to retain said

plunger within said barrel and an elongated lower body portion,
said lower body portion having a polygonal cross section and a tip having laterally spaced oppositely inclined surfaces,
said oppositely inclined surfaces on said plunger slope outwardly, laterally and upwardly away from said axis;
said plunger being depressible into contact with laterally spaced portions of said projecting hemispherical surface of said latch in alternative inclined positions thereof so that each successive depression of said plunger causes inclination of said latch in a direction opposite to that of the preceding depression and inclination of said latch.

2. A project-retract mechanism for a writing instrument having a barrel and a writing unit longitudinally movable therein between projected and retracted positions and spring means normally biasing the writing unit toward retracted position, said writing unit having an upper end and a lower writing tip at the other end, comprising:

a hollow barrel having an axially extending latch receiving aperture provided with opposing, laterally spaced side walls,
said side walls having a pair of longitudinally displaced and oppositely inclined project and retract stop shoulders,

the retract stop shoulder presenting a lower guide face portion at a smaller angle to the axis of said aperture and an upper guide face portion at a greater angle to said axis of said aperture terminating in said retract stop shoulder;

an elongated floating latch member contained within said barrel rearwardly of said writing unit,
said latch member being in contact with the upper end of said writing unit, movable with said unit and adapted to receive upward thrust of said spring biased writing unit,

said latch member and said barrel being cooperatively shaped to permit longitudinal sliding and inclination of the latch in opposite lateral directions and to restrain axial rotation of the latch,

said latch having a pair of opposed upstanding edge wall surfaces, a pair of opposed upstanding side wall surfaces and a top including a pair of separate oppositely inclined laterally spaced surfaces separated by a projecting central surface approximating a hemispherical form, said oppositely inclined laterally spaced surfaces adapted to cooperate with said laterally spaced stop shoulders in said barrel to retain said latch in alternately inclined positions of said latch to hold said writing unit in projected and retracted position,

each of said inclined surfaces intersecting said side wall surfaces to form an upper dihedral angle with one of said side wall surfaces of less than 90°, and also intersecting said edge walls to form an upper dihedral angle of less than 90° with one of said edge walls; and an axially aligned depressible plunger carried by the rear end of said barrel,

said plunger being depressible into contact with laterally spaced portions of said projecting hemispherical surface of said latch in alternative inclined positions thereof so that each successive depression of said plunger causes inclination of said latch in a direction opposite to that of the preceding depression and inclination of said latch.

3. A project-retract mechanism for a writing instrument having a barrel and a writing unit longitudinally movable therein between projected and retracted positions and spring means normally biasing the writing unit toward retracted position, said writing unit having an upper end and a lower writing tip at the other end, comprising:

a hollow barrel having an axially extending latch receiving aperture provided with opposing, laterally spaced side walls,

said side walls having a pair of longitudinally displaced and oppositely inclined project and retract stop shoulders,
 the retract stop shoulder presenting a lower guide face portion at a smaller angle to the axis of said aperture and an upper guide face portion at a greater angle to said axis of said aperture, terminating in said retract stop shoulder;
 an elongated floating latch member contained within said barrel rearwardly of said writing unit,
 said latch member being in contact with the upper end of said writing unit, movable with said unit and adapted to receive upward thrust of said spring biased writing unit,
 said latch member and said barrel being cooperatively shaped to permit longitudinal sliding and inclination of the latch in opposite lateral directions and to restrain axial rotation of the latch, and said latch member adapted to engage laterally spaced stop shoulders of said barrel to retain said latch in alternately inclined positions of said latch to hold said writing unit in projected and retracted position;
 an axially aligned depressible plunger carried by the rear end of said barrel,
 said plunger being depressible into contact with laterally spaced portions of said latch in alternative inclined positions thereof so that each successive depression of said plunger causes inclination of said latch in a direction opposite to that of the preceding depression and inclination of said latch.

4. In a writing instrument barrel for use with a project-retract mechanism for a writing unit, the provision of:

8
 a hollow barrel having an axially extending latch receiving aperture provided with opposing, laterally spaced side walls,
 said side walls having a pair of longitudinally displaced and oppositely inclined project and retract stop shoulders,
 an elongated floating latch member contained within said barrel and adapted to engage said longitudinally spaced stop shoulders,
 spring means within said barrel for biasing said latch member toward said stop shoulder,
 said retract stop shoulder presenting a lower guide face portion at a smaller angle to the axis of said aperture and an upper guide face portion at a greater angle to said axis of said aperture, terminating in said retract stop shoulder.

5. In a writing instrument barrel as stated in claim 4 wherein said retract stop shoulder upper guide face portion and said project stop shoulder form acute dihedral angles with said side walls.
